UNITED STATES PATENT OFFICE.

CORNELIUS J. CRONIN, OF ROUSEVILLE, PENNSYLVANIA.

IMPROVEMENT IN STILLS FOR REFINING OILS.

Specification forming part of Letters Patent No. 150,465, dated May 5, 1874; application filed March 21, 1874.

To all whom it may concern:

Be it known that I, CORNELIUS J. CRONIN, of Rouseville, in the county of Venango and State of Pennsylvania, have invented a new and Improved Still for Refining Petroleum, of which the following is a specification:

In the accompanying drawing, Figure 1 represents a vertical longitudinal section on the line C C, Fig. 2, of my improved still for refining crude petroleum.; Fig. 2, a horizontal section on the line x x, Fig. 1; and Fig. 3, a vertical transverse section of the same on the line y y, Fig. 2.

Similar letters of reference indicate corresponding parts.

The object of my invention is to construct, for the purpose of refining crude oil or petroleum, an improved still, in which the process of evaporating and distilling of the oil may be carried on with a considerable saving of fuel, and with greater rapidity, and also the formation of sediment on the bottom of the still be effectually prevented. The cleaning of the still is greatly facilitated, and not required as frequently as in the common stills in use. My invention consists of a still, of any suitable shape or size, which is provided with end chambers extending below the bottom of the still, into which the sediments are carried by a lateral traveling piece with adjustable scrapers moving along a longitudinal guide-screw turned by reciprocating gear.

In the drawing, A represents a still, of any approved shape, used in the refining of petroleum, being either of oblong, round, upright, or other form, and made of any suitable material. The bottom of the still is constructed in such a manner that a flush connection of the plates without any projecting rivet-heads or seams is produced. This connection is obtained by forming one edge of each bottom plate under suitable inclination, the other end being produced with the same inclination, and also with a flanged extension passing under the adjoining plate and connected thereto by rivets, which are countersunk at the inside of the bottom, as indicated in Fig. 1. The body of the still is set into the brick wall of the furnace in the usual manner, and the top provided with apertures a, leading, by connecting-tubes, to the condensers, and a man-hole, b,

through which the petroleum is supplied to the still and the attendant admitted for cleaning or repairing the still. The chambers or receptacles B are applied laterally at opposite sides of the still A, outside of the heating-surface, and extended below the bottom of the same. The bottom of each chamber B is curved or inclined from both sides toward the longitudinal axis, and provided at the lowermost point with an exit-hole, d, through which the sediment accumulating in the chambers is drawn off. The bottom of each chamber has, furthermore, a small hole, d', with plug or stop-cock for drawing off the water collecting at the bottom of the still. Openings e at both sides of chambers B serve to introduce the scrapers for cleaning out the bottom of the chambers. A guide-bolt, C, threaded along its full length, turns in suitable bearings in the outer walls of chambers B, and passes at suitable height from the bottom in longitudinal direction through the still. Screw-bolt C carries a lateral piece, D, which is provided with a series of vertical slotted scraper-plates D' sliding on guide-pins f of piece D. Piece D is grooved at the lower part, and carried by the turning of the screw with the scraper-plates D' along the bottom of the still. The scrapers D, being arranged throughout the full width of the still, slide along the smooth bottom of the same, and carry the sediment formed by the heavier oils and tar toward one of the lateral end chambers B, into which the same is deposited. As the scrapers yield readily in upward direction, they adjust themselves easily, and pass thereby over any unevenness formed on the bottom without interrupting the continuous working of the scrapers or breaking any one of them. The scrapers travel from one side to the other of the still during the process of distillation, and prevent thereby the formation of any sediments or non-conducting layers on the bottom of the still. A longitudinal rod, g, with stops g', slides in suitable bearings of the end chambers B, connects with the driving-belt, and is set in such a manner that the scrapers, when arrived at the farthest point, strike the stop g', and carry thereby the belt onto the reversing-pulley, changing thereby the rotation of the screw-bolt, and causing the return of the scrapers

in opposite direction till they arrive at the other end, where the same operation is repeated. A regular reciprocating motion of the scrapers is thus obtained, by which the sediments are continually carried into both chambers or receptacles, so that on account of the more direct action of the heat on the oil a more rapid evaporation, and therefore a saving of fuel, is obtained.

The still may be run for a considerable length of time without requiring cleaning, and the chambers are cleaned on stopping the still by the scrapers introduced through the side openings, and thus the sediments accumulated therein removed, the still being then ready for use again.

I am aware that it is not new to provide a still, used for distilling hydrocarbons, with a scraper, combined with a receiving device, said scraper being rotated during the process of distillation, and operating with relation to the bottom of the still and receiving device.

Having thus described my invention, I claim as new and desire to secure by Letters Patent—

1. The improved still for refining petroleum,

consisting of a still with end extension-chambers, and reciprocating scraper-plates for preventing the formation of the sediment on the bottom of the still, and carrying the same into the end receptacles, substantially as and for the purpose set forth.

2. A still for refining petroleum, provided with end chambers or receptacles extending below the bottom of the still, and having exit-holes for drawing off the accumulating sediment, and side openings for introducing the scraping instruments, as described.

3. The lateral piece D, arranged with sliding scrapers D' traveling on longitudinal screw-bolt C, in combination with the flush bottom of the still for gathering the sediment, as set forth.

4. The combination of lateral piece D, with scrapers D', with reversing-gear g g', for producing alternating reciprocating motion along the screw-bolt C, as specified.

CORNELIUS J. CRONIN.
